(57) **CLAIM**

The ornamental design for a multi tool and holder, as shown and described.

DESCRIPTION

FIG. 1 is top perspective view of a multi tool and holder, embodying my new design;

FIG. 2 is a bottom perspective view thereof;

FIG. 3 is a front elevational view thereof;

FIG. 4 is a rear elevational view thereof;

FIG. 5 is a left side elevational view of FIG. 1; the right side elevational view being a mirror image thereof;

FIG. 6 is a top plan view thereof;

FIG. 7 is a bottom plan view thereof;

FIG. 8 is an exploded perspective view thereof with a base cover;

FIG. 9 is a side elevational view thereof with the base cover engaged; and,

FIG. 10 is a top plan view of FIG. 9.

The broken lines are included for showing features that form no part of the claim.
